US0D1065510S

(12) **United States Design Patent** (10) **Patent No.:** **US D1,065,510 S**
(45) **Date of Patent:** **** Mar. 4, 2025**

(54) **FILTERED INHALATION DEVICE**

(71) Applicant: **Landon Duval**, San Clemente, CA (US)
(72) Inventor: **Landon Duval**, San Clemente, CA (US)
(**) Term: **15 Years**
(21) Appl. No.: **29/867,502**
(22) Filed: **Oct. 27, 2022**
(51) LOC (15) Cl. **29-02**
(52) U.S. Cl.
USPC **D24/110.2**
(58) **Field of Classification Search**

(57) **CLAIM**

The ornamental design of a filtered inhalation device, as shown and described.

DESCRIPTION

FIG. 1 is a perspective view of a filtered inhalation device, shown with temple bars extended;

FIG. 2 is a front view thereof;

FIG. 3 is a back view thereof;

FIG. 4 is a right-side view thereof;

FIG. 5 is a left side view thereof;

FIG. 6 is a top view thereof;

FIG. 7 is a bottom view thereof;

FIG. 8 is a perspective view of the filtered inhalation device, shown with temple bars folded;

FIG. 9 is a front view thereof;

FIG. 10 is a back view thereof;

FIG. 11 is a right-side view thereof;

FIG. 12 is a left side view thereof;

FIG. 13 is a top view thereof; and,

FIG. 14 is a bottom view thereof.

The broken lines in the drawing depict portions of the filtered inhalation device that form no part of the claimed design.
